UNITED STATES PATENT OFFICE.

GEORGE F. BALLOU, OF NEW YORK, N. Y.

MANICURE INSTRUMENT.

Application filed August 30, 1924. Serial No. 735,167.

To all whom it may concern:

Be it known that I, GEORGE F. BALLOU, a citizen of the United States, residing in the city, county, and State of New York, have **5** invented new and useful Improvements in Manicure Instruments, of which the following is a specification.

This invention relates to manicure instruments of the type which may be commonly **10** used by the public. An object of the invention is to provide an improved instrument of this type which will be so light and compact that it may be readily carried in hand bags or pockets, which may be made **15** largely from stamped and drawn sheet metal, which may be assembled in a simple and rapid manner, and which will be relatively inexpensive.

20 A further object is to provide a single improved instrument which will have the functions of a tweezer, a nail clip, a nail cleaner, a nail file and a letter opener. A further object is to provide an improved instrument of this type which may be locked **25** in its compact or closed condition.

Various other objects and advantages will appear from the following description of **30** an embodiment of the invention, and the novel features will be particularly pointed out hereinafter in the appended claims.

The invention comprehends a frame provided with a tweezer having any or all of **35** the features of a nail clip, nail file, nail cleaner and letter opener, in addition to the tweezer action, all constructed in an exceptionally simple, compact, durable and practical manner, as will be more particularly pointed out in the succeeding description of one embodiment of the invention.

40 In the accompanying drawing, Figure 1 is a top plan of an instrument constructed in accordance with the invention.

Fig. 2 is a side elevation of the same.

45 Fig. 3 is one end elevation of the same. Fig. 4 is an elevation of the opposite end of the same.

Fig. 5 is a longitudinal sectional elevation of the same.

50 Fig. 6 is a transverse sectional elevation of the same with the section taken substantially along the line 6-6 in Fig. 5.

Fig. 7 is another transverse sectional elevation of the same with the section taken substantially along the line 7-7 of Fig. 5.

Fig. 8 is a longitudinal sectional elevation **55** similar to Fig. 5 but with the parts in a different operative position, and

Fig. 9 is a bottom plan of the instrument.

In the illustrated embodiment of the invention, the frame 1 is somewhat channel **60** shaped, having side members 2 and a cross or base part 3 connecting the side members. Each side member 2 is provided with extensions 4 and 5 on opposite ends and the cross part 3 is provided upon one end with **65** an extension 6 running in the same general direction as the longer extensions 5 of the side member. The extension 6 of the cross or base part 3 is pointed at its tip, as indicated at 7, this pointed part serving as a **70** convenient tool for cleaning beneath the finger nails, and the extension 6 itself serving as a convenient instrument for opening letters. The free ends of the extensions 4 are connected by a pivot pin 8, this pin **75** being spaced in advance of an end edge 9 of the cross or base part 3, and also spaced slightly at one side of the plane of the cross part 3, so that there will be a passage between the pivot pin and the end edge 9 of **80** the cross part. The inner face of the cross part 3 immediately adjoining the end edge 9 serves as a fulcrum surface, as will presently appear.

A somewhat U-shaped strip 10 of spring **85** material, such as of spring steel, is inserted at its open end through the space between the pivot pin 8 and the edge 9 of the cross part 3 or the abutment surface (which is the inner face of the cross part 3), the arms **90** of the strip 10 being normally farther apart than the distance between the pin 8 and the edge 9, so that they will be under flexing stress toward one another when inserted into the frame. Thus when the arms **95** of the strip are released after being inserted between the pin and the abutment surface, they will spring apart and into contact with the abutment surface and the pivot pin. The surface of the arm of the strip 10 in **100** contact with the pivot pin is provided with a change in configuration 10^a of a nature to coact with the pin and prevent translation of the arm without limiting its rocking movement upon the pin. This change **105** in configuration may be conveniently provided by placing in that arm a transverse corrugation which partially embraces the

pivot pin. The stress of flexure in the arm with the indentation will hold the arm against the pivot pin with the indentation or corrugation in partial embracing relation with the pin until the arms of the U-shaped strip 10 are again flexed toward one another.

The outer end of the arm of the U-shaped strip which rocks upon the fulcrum surface upon the cross part 3 of the frame, at about 10 the point of contact with said surface, is bent toward the other arm, so that when the strip 10 is rotated upon the pivot pin in a direction to carry the base end toward the plane of the fulcrum surface, the free end 15 of the arm that is in contact with said surface will be forced toward the free end of the other arm of the strip faster than the other arm is rotated. This provides a 20 tweezers-like action between the free ends of the spring strip. In order to reduce the relative sliding action of the free end of one arm upon the other, as they approach, the free end of the arm engaging the pivot pin is bent slightly away from the other 25 arm. When the U-shaped strip is released, the tendency of the arms is to separate by reason of their resiliency and this will cause a rotation of the strip in a direction to carry the base end thereof away from the plane 30 of the fulcrum surface of the frame. This rotation will cause an opening or separation of the tweezer jaws.

The tip ends of the extensions 5 of the side members may be angular, as at 5^a, and 35 have aligned apertures 11 in which aligned lateral and integral ears 12 of a sheet metal stamping 13 may be rotatably disposed, with the stamping between the side walls 2 of the frame. This stamping extends between 40 the arms of the U-shaped spring strip and serves as a latch device therefor. This latch element serves as a stop for limiting rotation of the spring strip in a jaw opening direction (as shown in Fig. 8) and when the strip is rotated approximately to the limit 45 of its movement in a jaw closing direction (as shown in Fig. 2), the latch element or stamping may be swung into a position to abut an arm of the strip approximately normal thereto and lock it in that position within the frame. The tendency of the strip 10 to move out of the frame (by reason of its 50 resiliency) will cause a yielding pressure of the strip upon the end of the latch element in a direction passing through the pivotal axis of the latch element, and consequently the strip will hold the latch element in locking position. The locked position is shown in Figs. 5 to 7 of the drawing. The 55 latch element may have lateral fingers 13^a, integral therewith, which abut against the side edges of the angular ends 5^a when in this position, and thus limit movement of the element to any great extent past its locking position.

The free edge 14 of one or both side members 2 of the frame may be beveled or sharpened toward the inner faces of the side members for any portion of their length, and the width of the arms of the spring 70 strip 10 is approximately equal to the distance between the side members of the frame, so that the side edges of the arms will co-act scissors-like with the beveled side members and serve as nail clips. Thus as 75 an arm moves toward a bevelled edge 14 in a jaw closing direction it will co-act with said edge clip, scissors-like, and sever any object interposed between them.

Inasmuch as the U-shaped spring strip 10 80 is usually made of spring or hardened steel, the exposed face of one of the arms may be provided with a file surface 15 (see Fig. 9) serving as a nail file.

The pivot pin 8 is preferably a screw 85 or bolt passing between and through the side member extensions, which may be adjusted so as to draw the free beveled or knife edges of the frame toward one another, thus lessening the clearance between 90 said knife edges and the co-operating arm of the spring strip, to the extent desired to effect an efficient scissors-like or cutting action. A second screw or pin 16 may be passed between and through the side members, near the ends of the knife edges 14 farthest 95 from the pivot pin, so that the knife edges may be brought closer together to reduce the clearance with the arm of the spring strip uniformly along the entire 100 length of the knife edges. This second pin or screw may pass through the space between the arms of the spring strip so as not to interfere with the rotation of this strip.

In the manufacture and assembly of this 105 instrument, the channel-shaped frame may be formed from sheet metal by dies and stamping machines, and the latch element attached thereto. The pins 8 and 16 may next be passed between the side members 110 of the frame. The U-shaped spring strip is formed separately from stock strips of 115 spring steel, cut to proper lengths and bent into the desired shape before tempering or hardening. This spring strip may also have the file surface 15 placed thereon before it is hardened or tempered. The open end of the spring strip may, in a simple manner, be compressed together somewhat, and inserted through the space between the abutment 120 surface and the pivot pin and then released, whereupon the arms of the strip will separate and carry the indentation or transverse corrugation 10^a into embracing relation with the pivot pin 8, which locks the strip in the 125 frame until the strip is again compressed to quite an extent.

In the use of this instrument, the long tongue or extension 6 with its pointed tip 130 7 serves as a convenient and practical letter

opener, and the pointed tip serves as a convenient implement for cleaning beneath one's finger nails. The jaws provide a tweezers for toilet purposes, and an arm of the U-shaped strip and the knife edges of the side members of the frame provide a double nail clip or scissors. The nails after being clipped may be smoothed by rubbing the file surface 15 over the same. It will be observed that five different instruments are effectively combined in this simple, compact, inexpensive and durable structure. It will be understood, however, that any or all of these other features may be left off from the tweezers construction, if desired, but by combining them in this manner duplication of parts is prevented and a very compact, convenient and practical combination instrument is obtained.

20 It will be obvious that various changes in the details and arrangements of parts, which have been herein described and illustrated in order that the nature of the invention may be explained, may be made by those skilled in the art within the principle and scope of the invention, as expressed in the claims which are appended hereto as a part of the specification.

I claim:

30 1. In a manicure instrument, a frame element having a fulcrum surface and a pivot spaced above and endwise from said surface, and parallel thereto, and a U-shaped spring strip having the free ends of the arms thereof compressed toward one another and in that condition disposed between the pivot and fulcrum surface, whereby when the base of the U-shaped strip is pressed toward the plane of the fulcrum surface the free ends of the arms will be forced together to form tweezers.

45 2. In a manicure instrument, a frame element having a fulcrum surface and a pivot spaced above and endwise from said surface, and parallel thereto, and a U-shaped spring strip having the free end of the arms thereof compressed toward one another and in that condition disposed between the pivot and fulcrum surface, whereby when the base of the U-shaped strip is pressed toward the plane of the fulcrum surface the free ends of the arms will be forced together to form tweezers, the arm engaging the pivot and the pivot having a co-operative engagement preventing movement of that arm in either direction lengthwise of itself.

55 3. In a manicure instrument, a frame element having a fulcrum surface and a pivot spaced above and endwise from said surface, and parallel thereto, and a U-shaped spring strip having the free ends of the arms thereof compressed toward one another and in that condition disposed between the pivot and fulcrum surface, whereby when the base of the U-shaped strip is pressed to-

ward the plane of the fulcrum surface the free ends of the arms will be forced together to form tweezers, the arm engaging the pivot having in its surface that engages the pivot, an indentation which interlocks with said pivot to prevent movement of that arm endwise of itself, said arm remaining 70 in interlocking engagement with the pivot by reason of the tendency of the arms to separate from one another.

4. In a manicure instrument, a frame element having a fulcrum surface and a pivot spaced above and endwise from said surface, and parallel thereto, and a U-shaped spring strip having the free ends of the arms thereof compressed toward one another and in that condition disposed between the pivot and fulcrum surface, whereby when the base of the U-shaped strip is pressed toward the plane of the fulcrum surface the free ends of the arms will be forced together to form tweezers, said frame having a stop portion engaging with the base end portion of the U-shaped strip for limiting the rotation of the base of the strip upon said pivot and away from the frame when said base is released and the compressed arms try to separate.

5. In a manicure instrument, a frame element having a fulcrum surface and a pivot spaced above and endwise from said surface and parallel thereto, and a U-shaped spring strip having the free ends of the arms thereof compressed toward one another and in that condition disposed between the pivot and fulcrum surface, whereby when the base of the U-shaped strip is pressed toward the plane of the fulcrum surface the free ends of the arms will be forced together to form tweezers, the arm engaging the pivot and the pivot having a co-operative engagement preventing movement of that arm in either direction lengthwise of itself, said frame having a stop portion engaging with the base end portion of the U-shaped strip for limiting the rotation of the base of the strip upon said pivot and away from the frame when said base is released and the compressed arms try to separate.

6. In a manicure instrument, a frame element having a fulcrum surface and a pivot spaced above and endwise from said surface, and parallel thereto, and a U-shaped spring strip having the free ends of the arms thereof compressed toward one another and in that condition disposed between the pivot and fulcrum surface, whereby when the base of the U-shaped strip is pressed toward the plane of the fulcrum surface the free ends of the arms will be forced together to form tweezers, the arm engaging the pivot having in its surface that engages the pivot, an indentation which interlocks with said pivot to prevent movement of that arm endwise of itself, said arm remaining in in-

- terlocking engagement with the pivot by reason of the tendency of the arms to separate from one another, said frame having a stop portion engaging with the base end portion 5 of the U-shaped strip for limiting the rotation of the base of the strip upon said pivot and away from the frame when said base is released and the compressed arms try to separate.
- 10 7. In a manicure instrument, a frame element having a fulcrum surface and a pivot spaced above and endwise from said surface, and parallel thereto, and a U-shaped spring strip having the free ends of the arms there- 15 of compressed toward one another and in that condition disposed between the pivot and fulcrum surface, whereby when the base of the U-shaped strip is pressed toward the plane of the fulcrum surface the free ends 20 of the arms will be forced together to form tweezers, said frame having a latch device for releasably securing the base of the U-shaped strip at approximately its limit of movement against movement in a direction 25 away from the plane of the fulcrum surface.
8. In a manicure instrument, a frame element having a fulcrum surface and a pivot spaced above and endwise from said surface, and parallel thereto, and a U-shaped spring 30 strip having the free ends of the arms there- of compressed toward one another and in that condition disposed between the pivot and fulcrum surface, whereby when the base of the U-shaped strip is pressed toward the 35 plane of the fulcrum surface the free ends of the arms will be forced together to form tweezers, said frame having a latch device hinged to the frame between the arms of the U-shaped strip near the base portion thereof for limiting outward movement of the base portion about the axis of the said pivot and in a 40 direction away from said fulcrum surface, said latch device also limiting movement of the base of the strip about the pivot axis and in a direction away from the plane 45 of the fulcrum surface.
9. In a manicure instrument, a frame element having a fulcrum surface and a pivot spaced above and endwise from said surface, and parallel thereto, and a U-shaped spring 50 strip having the free ends of the arms there- of compressed toward one another and in that condition disposed between the pivot and fulcrum surface, whereby when the base of the U-shaped strip is pressed toward the 55 plane of the fulcrum surface the free ends of the arms will be forced together to form tweezers, the arm engaging the pivot and the pivot having a co-operative engagement preventing movement of that arm in either di- 60 rection lengthwise of itself, said frame having a latch device for releasably securing the base of the U-shaped strip at approximately its limit of movement against movement in a direction away from the plane of 65 the fulcrum surface.
10. In a manicure instrument, a frame element having a fulcrum surface and a pivot spaced above and endwise from said surface, and parallel thereto, and a U-shaped spring strip having the free ends of the arms there- 70 of compressed toward one another and in that condition disposed between the pivot and fulcrum surface, whereby when the base of the U-shaped strip is pressed toward the plane of the fulcrum surface the free ends of the arms will be forced together to form tweezers, the arm engaging the pivot having in its surface that engages the pivot, an indentation which interlocks with said pivot to prevent movement of that arm end- 75 wise of itself, said arm remaining in inter- 80 lock with the pivot by reason of the tendency of the arms to separate from one another.
11. In a manicure instrument, a frame element having a fulcrum surface and a pivot spaced above and endwise from said surface, and parallel thereto, a U-shaped spring strip having the free ends of the arms there- 85 of compressed toward one another and in that condition disposed between the pivot and fulcrum surface, whereby when the base of the U-shaped strip is pressed toward the plane of the fulcrum surface the free ends of the arms will be forced together to form tweezers, and a latch device hinged to the frame between the arms of the U-shaped strip near the base portion thereof for limiting outward movement of the base portion about the axis of the said pivot and in a 90 direction away from said fulcrum surface, said latch device having a length from its hinge axis such that when the base portion is forced toward the plane of the fulcrum surface to cause a tweezer-like approach of the free ends of the arms, its free end may swing into a position in which it is normal to the arm of the strip which it engages so as to lock the strip in that position.
12. In a manicure instrument, a frame element having a fulcrum surface and a pivot spaced below and endwise from said surface, and parallel thereto, and a U-shaped spring strip having the free ends of the arms there- 95 of compressed toward one another and in that condition disposed between the pivot and fulcrum surface, whereby when the base of the U-shaped strip is pressed toward the plane of the fulcrum surface the free ends of the arms will be forced together to form tweezers, the arm engaging the pivot having in its surface that engages the pivot, an indentation which interlocks with said pivot to prevent movement of that arm end- 100 wise of itself, said arm remaining in inter- 105 lock with the pivot by reason of the tendency of the arms to separate from one another.
13. In a manicure instrument, a frame element having a fulcrum surface and a pivot spaced above and endwise from said surface, and parallel thereto, and a U-shaped spring strip having the free ends of the arms there- 110 of compressed toward one another and in that condition disposed between the pivot and fulcrum surface, whereby when the base of the U-shaped strip is pressed toward the plane of the fulcrum surface the free ends of the arms will be forced together to form tweezers, the arm engaging the pivot having in its surface that engages the pivot, an indentation which interlocks with said pivot to prevent movement of that arm end- 115 wise of itself, said arm remaining in inter- 120 lock with the pivot by reason of the tendency of the arms to separate from one another.
14. In a manicure instrument, a frame element having a fulcrum surface and a pivot spaced above and endwise from said surface, and parallel thereto, and a U-shaped spring strip having the free ends of the arms there- 125 of compressed toward one another and in that condition disposed between the pivot and fulcrum surface, whereby when the base of the U-shaped strip is pressed toward the plane of the fulcrum surface the free ends of the arms will be forced together to form tweezers, the arm engaging the pivot having in its surface that engages the pivot, an indentation which interlocks with said pivot to prevent movement of that arm end- 130 wise of itself, said arm remaining in inter-

locking engagement with the pivot by reason of the tendency of the arms to separate from one another, and a latch device hinged to the frame between the arms of the U-shaped strip near the base portion thereof for limiting outward movement of the base portion about the axis of the said pivot and in a direction away from said fulcrum surface, said latch device having a length from its hinge axis such that when the base portion is forced toward the plane of the fulcrum surface to cause a tweezer-like approach of the free ends of the arms, its free end may swing into a position in which it is normal to the arm of the strip which it engages so as to lock the strip in that position.

13. In a manicure instrument, a frame element having a fulcrum surface and a pivot spaced below and endwise from said surface, and parallel thereto, a U-shaped spring strip having the free ends of the arms thereof compressed toward one another and in that condition disposed between the pivot and fulcrum surface, whereby when the base of the U-shaped strip is pressed toward the plane of the fulcrum surface the free ends of the arms will be forced together to form tweezers, the arm engaging the pivot and the pivot having a co-operative engagement preventing movement of that arm in either direction lengthwise of itself, and a latch device hinged to the frame between the arms of the U-shaped strip near the base portion thereof for limiting outward movement of the base portion about the axis of the said pivot and in a direction away from said fulcrum surface, said latch device having a length from its hinge axis such that when the base portion is forced toward the plane of the fulcrum surface to cause a tweezer-like approach of the free ends of the arms, its free end may swing into a position in which it is normal to the arm of the strip which it engages so as to lock the strip in that position.

14. In a manicure instrument, a channel frame having its side members extended from one end beyond the cross part, a pivot pin connecting the ends of said extensions and spaced from the plane of the cross part, and a U-shaped strip of spring material inserted at its open end between the pivot pin and the end of the cross piece with the arms of the strips flexed toward one another, whereby when the base end of the strip is moved toward the plane of the cross part the arms at the open end of the strip will be moved together tweezer-like.

15. In a manicure instrument, a channel frame having its side members extended from one end beyond the cross part, a pivot pin connecting the ends of said extensions and spaced from the plane of the cross part,

and a U-shaped strip of spring material inserted at its open end between the pivot pin and the end of the cross piece with the arms of the strips flexed toward one another, whereby when the base end of the strip is moved toward the plane of the cross part the arms at the open end of the strip will be moved together tweezer-like, and means carried by the frame for locking the base end of the strip in its position nearest to the plane of the cross part.

16. In a manicure instrument, a channel frame having its side members extended from one end beyond the cross part, a pivot pin connecting the ends of said extensions and spaced from the plane of the cross part, a U-shaped strip of spring material inserted at its open end between the pivot pin and the end of the cross piece with the arms of the strips flexed toward one another, whereby when the base end of the strip is moved toward the plane of the cross part the arms at the open end of the strip will be moved together tweezer-like, and a cross member on the frame through the loop at the base end of the strip for limiting the movement of the base end away from the plane of the cross part.

17. In a manicure instrument, a channel frame having its side members extended from one end beyond the cross part, a pivot pin connecting the ends of said extensions and spaced from the plane of the cross part, a U-shaped strip of spring material inserted at its open end between the pivot pin and the end of the cross piece with the arms of the strips flexed toward one another, whereby when the base end of the strip is moved toward the plane of the cross part the arms at the open end of the strip will be moved together tweezer-like, and a locking member hinged to the frame between the arms of the strip near its base end for limiting the movement of the base end away from the plane of the cross part, and movable about its hinge axis to abut endwise against an arm of the strip when the base end of the strip has moved into a position approximating that assumed when the tweezer jaws are closed, and thus lock the strip in that position.

18. In a manicure instrument, a channel frame having its side members extended from one end beyond the cross part, a pivot pin connecting the ends of said extensions and spaced from the plane of the cross part, and a U-shaped strip of spring material inserted at its open end between the pivot pin and the end of the cross piece with the arms of the strips flexed toward one another, whereby when the base end of the strip is moved toward the plane of the cross part the arms at the open end of the strip will be moved together tweezer-like, the arm of the

strip engaging the pivot pin and the pivot pin having co-operating engagement preventing movement of translation of that arm without limiting rotary movement of the 5 arm upon the pin.

19. In a manicure instrument, a channel frame having its side members extended from one end beyond the cross part, a pivot pin connecting the ends of said extensions 10 and spaced from the plane of the cross part, and a U-shaped strip of spring material inserted at its open end between the pivot pin and the end of the cross piece with the arms of the strips flexed toward one another, 15 whereby when the base end of the strip is moved toward the plane of the cross part the arms at the open end of the strip will be moved together tweezer-like, the arm of the strip engaging the pin having an indentation 20 partially embracing the pin for preventing translation of the strip without restricting its rotary movement upon the pin.

20. In a manicure instrument, a channel frame having its side members extended 25 from one end beyond the cross part, a pivot pin connecting the ends of said extensions and spaced from the plane of the cross part, a U-shaped strip of spring material inserted at its open end between the pivot pin and 30 the end of the cross piece with the arms of the strips flexed toward one another, whereby when the base end of the strip is moved toward the plane of the cross part the arms at the open end of the strip will be 35 moved together tweezer-like, the arm of the strip engaging the pivot pin and the pivot pin having co-operating engagement preventing movement of translation of that arm without limiting rotary movement of the 40 arm upon the pin, and a cross member on the frame through the loop at the base end of the strip for limiting the movement of the base end away from the plane of the cross part.

45. 21. In a manicure instrument, a channel frame having its side members extended from one end beyond the cross part, a pivot pin connecting the ends of said extensions and spaced from the plane of the cross part, 50 a U-shaped strip of spring material inserted at its open end between the pivot pin and the end of the cross piece with the arms of the strips flexed toward one another, whereby when the base end of the strip is moved 55 toward the plane of the cross part the arms at the open end of the strip will be moved together tweezer-like, the arm of the strip engaging the pivot pin and the pivot pin having co-operating engagement preventing 60 movement of translation of that arm without limiting rotary movement of the arm upon the pin, and a locking member hinged to the frame between the arms of the strip near its base end for limiting the movement 65

of the base end away from the plane of the cross part, and movable about its hinge axis to abut endwise against an arm of the strip when the base end of the strip has moved into a position approximating that assumed when the tweezer jaws are closed, and thus 70 lock the strip in that position.

22. In a manicure instrument, a channel frame having its side members extended from one end beyond the cross part, a pivot pin connecting the ends of said extensions 75 and spaced from the plane of the cross part, a U-shaped strip of spring material inserted at its open end between the pivot pin and the end of the cross piece with the arms of the strips flexed toward one another, whereby when the base end of the strip is moved toward the plane of the cross part the arms at the open end of the strip will be moved together tweezer-like, the arm of the strip 80 engaging the pin having an indentation partially embracing the pin for preventing translation of the strip without restricting its rotary movement upon the pin, and a cross member on the frame through the loop at the base end of the strip for limiting the 85 movement of the base end away from the plane of the cross part.

23. In a manicure instrument, a channel frame having its side members extended 90 from one end beyond the cross part, a pivot pin connecting the ends of said extensions and spaced from the plane of the cross part, a U-shaped strip of spring material inserted at its open end between the pivot pin and the end of the cross piece with the arms of the strips flexed toward one another, whereby when the base end of the strip is moved toward the plane of the cross part the arms at the open end of the strip will be moved together 95 tweezer-like, the arm of the strip engaging the pin having an indentation partially embracing the pin for preventing translation of the strip without restricting its rotary movement upon the pin, and a cross member on the frame through the loop at the base end of the strip for limiting the movement of the base end away from the plane of the cross part.

100 24. In a manicure instrument, a frame having a fulcrum pin and an abutment edge spaced from the pin, and a U-shaped spring strip having its open end inserted between the pin and edge, with the free ends of the arms flexed toward one another, an arm of the strip and the pin having a coaction permitting rotating and preventing translation 105 of the strip while in contact with the pin, 110

whereby when the strip is rotated about the pivot pin, the arm not in engagement with the pin will be cammed by the abutment edge toward the free end of the other arm to form therewith tweezers jaws.

25. In a manicure instrument, a frame having a fulcrum pin and an abutment edge spaced from the pin, and a U-shaped spring strip having its open end inserted between the pin and edge, with the free ends of the arms flexed toward one another, an arm of the strip and the pin having a coaction permitting rotating and preventing translation of the strip while in contact with the pin,

10 whereby when the strip is rotated about the pivot pin, the arm not in engagement with the pin will be cammed by the abutment edge toward the free end of the other arm to form therewith tweezers jaws, the free end of the

15 arm engaging the abutment edge being bent slightly toward the other arm so that sliding movement of the jaws will be minimized.

26. In a manicure instrument, a frame having a fulcrum pin and an abutment edge spaced from the pin, and a U-shaped spring strip having its open end inserted between the pin and edge, with the free ends of the arms flexed toward one another, an arm of the strip and the pin having a coaction permitting rotating and preventing translation of the strip while in contact with the pin,

20 whereby when the strip is rotated about the pivot pin the arm not in engagement with the pin will be cammed by the abutment edge toward the free end of the other arm to form therewith tweezers jaws, the free end of the

25 arm engaging the abutment edge being bent slightly toward the other arm so that sliding movement of the jaws will be minimized.

27. In a manicure instrument, a frame having a fulcrum pin and an abutment edge spaced from the pin, and a U-shaped spring strip having its open end inserted between the pin and edge, with the free ends of the arms flexed toward one another, an arm of the strip and the pin having a coaction permitting rotating and preventing translation of the strip while in contact with the pin,

30 whereby when the strip is rotated about the pivot pin the arm not in engagement with the pin will be cammed by the abutment edge toward the free end of the other arm to form therewith tweezers jaws, the frame having a sharpened edge co-operating with one of the arms of the strip to form a nail clip operated by rotation of the strip about the

35 pivot pin.

28. In a manicure instrument, a frame having a fulcrum pin and an abutment edge spaced from the pin, and a U-shaped spring strip having its open end inserted between the pin and edge, with the free ends of the arms flexed toward one another, an arm of the strip and the pin having a coaction permitting rotating and preventing translation of the strip while in contact with the pin,

40 whereby when the strip is rotated about the pivot pin the arm not in engagement with the pin will be cammed by the abutment edge toward the free end of the other arm to form therewith tweezers jaws, the exposed

45 face of the outer arm of the strip having a file surface serving as a convenient nail file.

28. In a manicure instrument, a frame having a fulcrum pin and an abutment edge spaced from the pin, and a U-shaped spring strip having its open end inserted between the pin and edge, with the free ends of the arms flexed toward one another, an arm of the strip and the pin having a coaction permitting rotating and preventing translation of the strip while in contact with the pin,

45 whereby when the strip is rotated about the pivot pin the arm not in engagement with the pin will be cammed by the abutment edge toward the free end of the other arm to form therewith tweezers jaws, the frame

50 having a sharpened edge co-operating with one of the arms of the strip to form a nail clip operated by rotation of the strip about the pivot pin, and the exposed face of the outer arm of the strip having a file surface

55 serving as a convenient nail file.

29. In a manicure instrument, a channel frame having its side members extended from one end beyond the cross part, a pivot pin connecting the ends of said extensions and spaced from the plane of the cross part, a U-shaped strip of spring material inserted at its open end between the pivot pin and the end of the cross piece with the arms of the strips flexed toward one another, whereby when the base end of the strip is moved toward the plane of the cross part the arms at the open end of the strip will be moved together tweezers-like, the cross part having a free pointed extension in a direction away from the tweezer jaws and serving as a letter opener and nail cleaner.

30. In a manicure instrument, a channel frame having its side members extended from one end beyond the cross part, a pivot pin connecting the ends of said extensions and spaced from the plane of the cross part, a U-shaped strip of spring material inserted at its open end between the pivot pin and the end of the cross piece with the arms of the strips flexed toward one another, whereby when the base end of the strip is moved toward the plane of the cross part the arms at the open end of the strip will be moved together tweezers-like, one of the side members of the channel frame having a sharpened edge co-operating with an arm of the strip to serve as a nail clip.

In testimony whereof I have hereunto set my hand.

GEORGE F. BALLOU.
